UNITED STATES PATENT OFFICE.

WILLIAM F. HELMOND, OF HARTFORD, CONNECTICUT, ASSIGNOR TO
UNDERWOOD TYPEWRITER COMPANY, OF NEW YORK, N. Y., A
CORPORATION OF NEW JERSEY.

RIBBON-REVERSING MECHANISM FOR TYPE-WRITERS.

SPECIFICATION forming part of Letters Patent No. 740,651, dated October 6, 1903.

Application filed March 5, 1903. Serial No. 146,321. (No model.)

To all whom it may concern:

Be it known that I, WILLIAM F. HELMOND, a citizen of the United States, and a resident of Hartford, Hartford county, Connecticut, have 5 invented certain new and useful Improvements in Ribbon-Reversing Mechanisms for Type-Writers, of which the following is a specification.

My invention relates to type-writing machines and the like in which a printing-ribbon is shifted during the operation of the machine, so as to secure a uniform wear of the ribbon, and in which the direction of the ribbon-feed is periodically reversed.

15 The object of my invention is to provide a mechanism of the above-indicated class that will operate with certainty and with the expenditure of very little power, so that the reversing of the ribbon will take place at the 20 right moment without putting any undue strain on delicate parts, such as the ribbon itself.

25 My invention will now be fully described with reference to the accompanying drawings, and the features of novelty will then be pointed out in the appended claims.

Figure 1 is a plan of a portion of a type-writer provided with my improvement. Fig. 2 is a front elevation. Fig. 3 is a sectional elevation on line 3 3 of Fig. 2. Fig. 4 is an elevation from the right-hand side of Fig. 2. Fig. 5 is a detail sectional elevation of the means for locking the reversing mechanism in either one of its positions. Fig. 6 is a detail sectional elevation illustrating the elastic means for shifting the reversing-shaft.

Each of the ribbon-spools A is carried upon a shaft B, journaled in a frame C of the machine, and provided at its lower end with a 40 beveled wheel B'. These wheels are adapted for alternate engagement with beveled pinions D' D², which are rigidly secured upon the reversing-shaft D, which is mounted in bearings C', not only to turn but to slide in them. The distance between the beveled pinions D' D² is less than the distance between the two beveled wheels B', so that only one of the pinions can be in mesh at a time. Upon one end of the shaft is mounted a crank D³

for the purpose of manually adjusting the 50 ribbon E. With the shaft is further connected, as by means of an arm D⁴ on the crank D³, a ratchet-wheel F, engaged by a spring-pawl G to prevent a return movement of the ratchet-wheel, the said pawl being secured 55 to a fixed portion of the frame.

By reference to Fig. 2 it will be seen that the end of the arm D⁴ which engages the ratchet-wheel F is parallel with the shaft D, so that the shaft, with the said arm, may be 60 moved lengthwise, bringing the arm out of engagement with the ratchet-wheel, which latter does not share the longitudinal motion of the shaft, but is journaled on a suitable bearing C². An intermittent rotation is im- 65 parted to the shaft D in any suitable manner, as by means of the feed-pawl H, which a spring H' presses against the ratchet-wheel F, the said pawl being pivotally connected at H² with a crank-arm I' upon a shaft. This 70 shaft has another crank-arm I², located centrally and connected with an arm J at J'. This arm is secured upon a rock-shaft K, which also carries arms L, connected with a frame M, operated by the universal bar. The 75 universal bar may also be connected with the central ribbon-guide N in any suitable manner.

It will be understood that mechanism for imparting an intermittent rotation to the reversing-shaft D and for actuating the ribbon-guide forms no part of my present invention.

Adjacent to each ribbon-spool I prefer to arrange a stationary ribbon-guide O, preferably carried by a bracket O'. Between the 85 two end ribbon-guides O and adjacent to each of them I locate a movable ribbon-guide P, preferably U-shaped, as shown best in Fig. 3. Each of these movable guides is carried by a crank-arm P' upon a shaft P², which is journaled in stationary bearings P³, adjacent to the bearings of the shaft B. The lower end of each shaft P² is bent so as to clear the beveled wheel B' and is then further bent to extend to the side and preferably also under 90 the reversing-shaft D, as shown at P⁴. These portions P⁴ of the shafts P² form crank portions adapted to engage collars Q, which are

slidable lengthwise upon the shaft D, the arrangement being such that the crank portion P⁴ is between the collar Q and the beveled pinion D' or D². The collar Q is normally 5 pressed toward the crank portion P⁴ by a spring R, coiled around the shaft D and having its other end in engagement with a collar S, which is rigidly secured upon the shaft D or at least is held to slide therewith. The 10 ribbon E is provided near its ends with suitable projections E', adapted to collide with the corresponding movable guides P, so that as the end of the ribbon winds off the spool the corresponding guide P will be swung in 15 such a manner as to press the collar Q toward the collar S. In order that the shaft D may be shifted suddenly, I provide suitable mechanism for retarding the shifting of the shaft until the crank portion P⁴ has moved to a 20 certain extent. This mechanism, as shown, consists of two grooves D⁵, provided at one end of the shaft D and adapted to be engaged by a ball T, which is pressed into either one of said grooves by a spring U, the tension of 25 which may be adjusted by means of a set-screw V. The spring and set-screw are contained in a sleeve W, which is adjustable in the frame of the machine toward and from the shaft D and which may be held in its adjusted position by means of a set-screw X.

It will be understood that the movement of the movable guide P and the resultant movement of the crank portion P⁴ will at first only compress the spring R until the tension of 30 said spring will be sufficient to overcome the resistance which is opposed to the longitudinal movement of the shaft D by the retarding and locking ball T. Thus in Fig. 2 the spring R at the right-hand portion of the machine is shown in a compressed condition at 35 the moment immediately preceding the shifting of the shaft D. When the tension of the compressed spring is sufficient, the ball T will rise on the curved or inclined surface of the groove D⁵ and the spring R will expand and throw the shaft D from left to right. This 40 throws the beveled pinion D² into engagement with the beveled wheel B', and thus causes the ribbon to be reversed. A similar 45 action will take place when the other end of the ribbon reaches its movable guide P. The longitudinal motion of the shaft D is limited partly by the contact of the beveled pinions D' D² with the corresponding beveled wheels, 50 partly by the action of the ball T in conjunction with the grooves D⁵, and partly by the 55 engagement of the collars S with the frame portions or bearings C'.

It will be seen that the action is a positive 60 one, and that while the ribbon acts gradually upon the mechanism which finally brings about the reversal the reversing mechanism

itself is shifted suddenly, thus securing a positive action.

Various modifications may be made with- 65 out departing from the nature of my invention.

What I claim as new, and desire to secure by Letters Patent, is—

1. In a type-writing machine or the like, the 70 combination of a movable ribbon-guide, means for feeding the ribbon, mechanism for reversing the direction of the ribbon-feed and a yielding connection between the movable ribbon-guide and the ribbon-reversing mechan- 75 ism.

2. In a type-writing machine or the like, the combination with the shafts or spindles of the ribbon-spools, of a longitudinally-slidable shaft arranged to drive one or the other of 80 the ribbon-spool spindles, means for rotating said shaft, a movable ribbon-guide, and means operated by the movement of said ribbon-guide for shifting the said shaft.

3. In a type-writing machine or the like, the 85 combination of the ribbon-spool spindles, a longitudinally-slidable shaft adapted to drive one or the other of said spindles, collars slidable on said shaft, movable ribbon-guides, an operative connection from each of said guides 90 to the corresponding collar to shift the latter by the movement of the ribbon-guide, and a spring through the medium of which the movement of the collar is transmitted to the shaft when the spring has acquired the requisite 95 tension.

4. In a type-writing machine or the like, the combination of the ribbon-spool spindles, a longitudinally-slidable shaft adapted to drive one or the other of said spindles, movable 100 ribbon-guides, means for shifting said shaft by the movement of the ribbon-guides, and a retarding device for opposing a resistance to the longitudinal movement of said shaft.

5. In a type-writing machine or the like, the 105 combination of the ribbon-spool spindles, a longitudinally-slidable shaft adapted to drive one or the other of said spindles, a retarding device engaging said shaft and pressed against the same transversely to oppose a resistance to the longitudinal movement of the shaft, 110 movable ribbon-guides, collars loosely mounted on shaft so as to be capable of sliding thereon, a yielding connection between each collar and said shaft, and an operative connection from each ribbon-guide to the corresponding collar. 115

In testimony whereof I have signed my name to this specification in the presence of two subscribing witnesses.

WILLIAM F. HELMOND.
